G. F. GOELZ.
GARMENT HANGER.
APPLICATION FILED DEC. 9, 1914.

1,173,421.

Patented Feb. 29, 1916.

UNITED STATES PATENT OFFICE.

GEORGE F. GOELZ, OF WEST NEW YORK, NEW JERSEY.

GARMENT-HANGER.

1,173,421.

Specification of Letters Patent. Patented Feb. 29, 1916.

Application filed December 9, 1914. Serial No. 876,281.

To all whom it may concern:

Be it known that I, GEORGE F. GOELZ, a citizen of the United States, and residing at West New York, in the county of Hudson and State of New Jersey, have invented 5 certain new and useful Improvements in Garment-Hangers, of which the following is a specification, such as will enable those skilled in the art to which it appertains to 10 make and use the same.

This invention relates to garment hangers, and the object thereof is to provide an improved device of this class which is designed for use in closets, wardrobes and 15 similar places, and particularly for use in closets or wardrobes having transverse shelves in the top thereof; a further object being to provide a garment hanger which is simple in construction and comparatively 20 inexpensive, and which may be quickly and easily applied for use in closets or wardrobes of the class specified.

The invention is fully disclosed in the following specification, of which the accompanying drawing forms a part, in which the separate parts of my improvement are 25 designated by suitable reference characters in each of the views, and in which:—

Figure 1 is a sectional view showing the 30 construction, application and use of my improved garment hanger; Fig. 2 a partial section on the line 2—2 of Fig. 1; Fig. 3 a partial section on the line 3—3 of Fig. 4; and, Fig. 4 a side and end view of a modified form of a detail of construction shown 35 in Fig. 1.

In the drawing forming part of this specification, I have shown at *a* the back wall of an ordinary clothes closet or wardrobe to which is secured a back board *b* over which is placed a shelf *c*, all this construction being of the usual form and forming no part of my invention.

In the practice of my invention, I provide 45 a garment hanger, comprising a tube *d* in which is placed a telescopic rod *e* which is pointed at its outer end as shown at *e*² and adapted to be driven into the board *b*. The tube *d* is provided at its outer end with 50 a knob or head *f* through which is passed a yoke-shaped device *g* provided with two diverging side arms *g*² having backwardly directed hook members *g*³ provided with downwardly directed points *g*⁴. The yoke-

shaped device *g* is detachable from the knob 55 or head *f* to facilitate the packing and shipping of the device and is also rotatable in said knob or head. In the use of this device, the pointed end of the rod *e* is driven into the board *b* after which said 60 rod, or the free end thereof, is inserted into the tube *d*, or said tube is passed on over the outer end of said rod, after which the yoke-shaped device *g* having been connected with the knob or head *f* of said tube and 65 swung into the vertical position in Fig. 1 and so that the angular hook members *g*³ will extend backwardly over the shelf *c* and the points *g*⁴ of said hook members may be driven down into said shelf as shown. 70 When thus placed in position the hanger proper consisting of the tube *d* and rod *e* ranges forwardly and backwardly in the closet or wardrobe and as the rod *e* is free to slide in the tube *d*, the length of this part 75 of the device may be adjusted to suit the width of the shelf *c*, as will be readily understood, and when placed in position as shown and described an ordinary coat or similar hanger *h* having a hook *h*², or any 80 number of said devices, may be suspended from the parts *d*—*e* as shown in Figs. 1 and 2.

Instead of providing the knob or head *f* on the outer end of the tube *d*, as shown in 85 Fig. 1, said outer end of said tube may be provided with projecting ears or similar devices *i* having holes *i*² through which the yoke-shaped member *g* may be passed, as will be readily understood, and as shown in 90 Figs. 3 and 4, and other changes in and modifications of the construction herein described may be made, within the scope of the appended claim, without departing from the spirit of my invention or sacrificing its 95 advantages, and it will also be understood that the back board *b* is not an absolute necessity as the pointed end *e*² of the rod *e* may be driven into the back wall of the closet or wardrobe, if desired.

Having fully described my invention, what I claim as new and desire to secure by Letters Patent, is:—

A garment hanger designed for use in a 105 closet or wardrobe having a top shelf, said hanger being composed of telescopic members one of which is pointed at its outer end and adapted to be forced into the back wall

of the closet and the other being provided at its outer end with a hinged hook-shaped device adapted to be swung over and engage the top of the shelf near the front edge thereof.

In testimony that I claim the foregoing as my invention I have signed my name in

presence of the subscribing witnesses this 7th day of December, 1914.

GEORGE F. GOELZ.

Witnesses:

C. MULREANY,
H. E. THOMPSON.
